TOY SEWING MACHINE

Ronald G. Martelet, Chicago, Ill., assignor to Sears, Roebuck and Co., Chicago, Ill.

Filed Dec. 22, 1970, Ser. No. 26,622

Term of patent 14 years

Int. Cl. D15—06

U.S. Cl. D70—1

FIG. 1 is a front elevational view of a toy sewing machine showing my new design;

FIG. 2 is an end elevational view taken from the right of FIG. 1, the base portion being broken away for convenience of illustration;

FIG. 3 is a top plan view thereof;

FIG. 4 is a rear elevational view thereof;

FIG. 5 is an end elevational view taken from the left of FIG. 1, the base portion being broken away for convenience of illustration;

FIG. 6 is a transverse cross sectional view taken substantially on line 6—6 of FIG. 1;

FIG. 7 is a transverse cross sectional view taken substantially on line 7—7 of FIG. 1;

FIG. 8 is a transverse cross sectional view taken substantially on line 8—8 of FIG. 1, and

FIG. 9 is a transverse cross sectional view taken substantially on line 9—9 of FIG. 1.

I claim:

The ornamental design for a toy sewing machine, as shown and described.
